UNITED STATES PATENT OFFICE.

WILLIAM S. MCLEWEE, OF TRENTON, NEW JERSEY.

DESIGN FOR A LAMP-SHADE.

SPECIFICATION forming part of Design No. 21,577, dated May 24, 1892.

Application filed April 30, 1892. Serial No. 431,358. Term of patent 7 years.

To all whom it may concern:

Be it known that I, WILLIAM S. MCLEWEE, a citizen of the United States, and a resident of Trenton, Mercer county, and State of New Jersey, have invented a new and original Design for Lamp-Shades, of which the following is a specification, reference being had to the accompanying drawing, forming a part thereof.

10 Referring to the drawing, the figure represents a side view of a lamp-shade formed according to my design.

15 The leading feature of my design consists in the ornamental flange or collar surrounding the opening in the top of the shade.

20 *a* represents the body of the shade, and *b* the flange or collar surrounding the opening in the top of the same. The flange or collar *b* is surrounded at its point of union with the body *a* by a raised bead or collar *c* and extends from the latter in a long outwardly-tapering line to a point *b'*, from which it ex-

tends in a short tapering line inwardly to a point *b²* and terminates from the latter in a short vertical line, as at *b³*. The surface of the upper tapering portion of the flange or collar *c* is ribbed or scalloped, as shown at *d*, and on the lower tapering portion of the same is arranged a series of raised ornamental portions *e*, each of which consists of several ribs *e'*, which taper from their lower end at the edge of the bead or collar *b* into an enlarged upper end and are arranged in close proximity to each other, as shown.

Having thus set forth my invention, what I claim, and desire to secure by Letters Patent of the United States, is—

The design for a lamp-shade, as herein shown and described.

WILLIAM S. MCLEWEE.
